UNITED STATES PATENT OFFICE.

HENRY J. GILBERT, OF SAGINAW, MICHIGAN.

DESIGN FOR SHEET GLASS.

Application filed February 12, 1923. Serial No. 5,153. Term of patent 14 years.

To all whom it may concern:

Be it known that I, HENRY J. GILBERT, a citizen of the United States, residing at Saginaw, in the county of Saginaw and State of Michigan, have invented a new, original, and ornamental Design for Sheet Glass, of which the following is a specification, reference being had to the accompanying drawing, forming part thereof.

Fig. 1 is a plan view.

Fig. 2 is a transverse section on the line 2—2 of Fig. 1.

I claim the ornamental design for sheet glass.

HENRY J. GILBERT.
